REED SETTING GAUGE FOR LOOMS

Clifford Darwin, Paxton, Mass., assignor to
Crompton & Knowles Loom Works, Worcester,
Mass., a corporation of Massachusetts

Application December 30, 1948, Serial No. 68,250

20 Claims. (Cl. 139—1)

1

This is a continuation in part of co-pending application Serial No. 31,264, filed June 5, 1948, now abandoned.

This invention relates to reed setting gauges for looms and it is the general object of the invention to provide a simple form of gauge by which the weft beat-up reed may be utilized to effect correct positioning of the fell of the cloth.

In the weaving of many types of fabric difficulty is experienced in avoiding starting marks which are produced when the loom resumes weaving after a period of idleness. If a loom is at rest for any length of time it is found that the tension of the warp threads tends to move the fell of the cloth rearwardly and if the loom is started up after a period of rest the first pick is too close to the last pick which was led before the period of rest started. If a loom is idle overnight the rearward movement of the fell due to tension of the warp may be an amount equal to several picks. In the past considerable skill has been required on the part of the weaver to estimate how far the fell of the cloth should be moved forwardly to compensate for its rearward movement due to warp tension. No satisfactory means has thus far been developed which will permit resumption of weaving after an extended rest period with assurance that there will be no starting mark in the cloth.

Looms of the type to which the invention more particularly relates are generally provided with some form of so-called swing reed which is resiliently mounted on the lay in such manner as to yield rearwardly relatively to the lay at the time of beat-up. In the usual procedure when resuming weaving after a period of rest the weaver advances the cloth by manipulation of the take-up mechanism until the cloth fell is thought to be in correct position, but it is difficult to determine how much the reed yields and for this reason the fell is not always correctly placed and may be either behind or in front of its correct position.

It is an important object of the present invention to provide a simple gauge means by which the weaver can readily determine the amount by which the fell of the cloth must be advanced to locate it in its correct position. The gauge comprises two parts, one on the lay and the other on the reed, which will be set to be aligned with the lay on front center during a period of weaving. After a period of looms stoppage the lay is moved to front center, and if the reed is in an abnormal rear position relatively to the lay due to rearward movement of the fell of the cloth

2

the gauge parts will be out of register and the weaver will advance the take-up to move the fell forwardly until the two parts of the gauge are again in register, thereby indicating that the fell of the cloth is in correct position for the resumption of weaving.

In the description which follows three forms of gauge are shown, all operating on the same general principle already set forth hereinbefore. One form of the invention utilizes two gauge parts which are brought into vertical alignment by horizontal movement of the reed relatively to the lay, but in the other two forms of the invention the indicators of the two parts of the gauge are in lineal alignment when registering.

It is a more specific object of the invention to provide two identical gauge parts or members each having two indicators at right angles to each other and each having a wall or foot parallel to one of the indicators thereof. When two such gauge members are applied one to the lay and the other to the swing reed each will have an indicator parallel to the lay, and registry of these indicators can be effected by movement of the reed relatively to the lay.

Spring reeds are usually acted upon by at least two springs, one at each end thereof, which normally hold the reed against the lay or some part of it when the lay is behind its front center or beat-up position. These springs yield at beat-up when the lay is on front center and the amount of yielding will ordinarily depend upon the forces exerted by the springs. If one spring is set to exert more force than the other its end of the reed will yield less than the other end with the result that the beat-up is not uniform at both sides of the cloth.

It is another object of the present invention to provide a reed setting gauge at each side of the loom by which the weaver can determine whether the springs at the ends of the reed are exerting equal forces. If one spring is found to be weaker or stronger than the other it can be adjusted until it offers the same resistance to yielding as does the other springs.

With these and other objects in view which will appear as the description proceeds, the invention resides in the combination and arrangement of parts hereinafter described and set forth.

In the accompanying drawings, wherein three convenient embodiments of the invention are set forth,

Fig. 1 is a side elevation partly in section of the forward end of one side of a loom having the preferred form of the invention applied thereto;

Fig. 2 is an enlarged rear elevation looking in the direction of arrow 2, Fig. 1.

Fig. 3 is a vertical section on line 3—3, Fig. 2.
Fig. 4 is an enlarged horizontal section on line 4—4, Fig. 2.

Figs. 5 and 6 are diagrammatic views illustrating the manner of operating the preferred form of the invention.

Fig. 7 is a plan view of the lay showing the reed setting gauge adjacent each end thereof.

Fig. 8 is a view similar to Fig. 1, but showing the first modified form of the invention.

Fig. 9 is an enlarged front elevation looking in the direction of arrow 9, Fig. 8.

Fig. 10 is a plan view looking in the direction of arrow 10, Fig. 9.

Fig. 11 is a vertical section on line 11—11, Fig. 10.

Fig. 12 is a diagrammatic view similar to Fig. 7.

Fig. 13 is a view similar to a portion of Fig. 9, but showing the second modification of the invention which utilizes two identical gauge members.

Fig. 14 is a horizontal section on line 14—14, Fig. 13, and

Fig. 15 is a bracketed view showing in perspective the two identical parts of the gauge shown in Fig. 13.

Referring particularly to Figs. 1 to 7, wherein the preferred form of the invention is shown as applied to the form of swing reed shown in U. S. Patent to Holmes No. 1,926,382, the loom frame 10 supports a top shaft 11 which by means of connectors 12 cause back and forth reciprocation of the lay 13 as the shaft rotates. The connectors drive the lay by means of pins 14 each of which passes through a pair of ears 15 projecting rearwardly from the lay. A hand wheel 16 on shaft 11 affords means for manually moving the lay backwardly and forwardly. The lay has an upwardly extending horn 17 at each end thereof on which a bearing 18 is vertically adjustable relatively to the lay.

A hand rail 19 extending across the loom has bolted to each end thereof a carrier 20 provided with a stud 21 rockable in the corresponding bearing 18. The reed 22 has its top rail 23 clamped against angle section 24 secured to the hand rail and has its bottom rail 25 normally held forwardly against part of the lay by a backstay 26 extending across the lay.

Engaging each end of the backstay is a resilient positioner, designated generally at 27, pivoted on a stud 28 fixed to the lay. A spring 29 for each positioner the force of which is adjustable as at 30 tends normally to hold the bottom rail 25 in forward position relatively to the lay, but yields to permit pivotal rearward movement of the bottom of the reed by the fell of the cloth when the lay moves to front center. Each end of the backstay is connected to the corresponding end of angle section 24 by a tie member 31.

Reed elements similar to that already described are generally known as swing reeds. For an understanding of further details of the lay and reed reference may be had to the previously mentioned Holmes patent.

Looms ordinarily have cloth take-up mechanisms one example of which is shown in Fig. 1. The cloth C is wrapped around a take-up roll 35 turned by means of a train of gears including a ratchet wheel 36 which is advanced in a counter-clockwise direction as viewed in Fig. 1 during loom operation. A feed pawl 37 and hold pawl 38 are of usual construction and can be lifted to permit manual reverse movement of the ratch-

et wheel, or yield when the ratchet wheel is advanced manually. Further description of the take-up is not thought necessary, and it will suffice for present purposes to state that when the ratchet wheel is advanced manually of the cloth fell F is moved forwardly.

The matter thus far described is of common construction and is given herein as examples of swing reeds and take-ups usable with the present invention.

As already stated the fell of the cloth is likely to move rearwardly during a period of loom stoppage with the result that upon resumption of weaving a thick place or starting mark will be formed in the cloth. It is the general purpose of this invention to provide a gauge having indicators which can be aligned by manipulation of the take-up when weaving is resumed to avoid the aforesaid starting marks.

In carrying the preferred form of the invention into effect the loom is provided with gauges GR and GL located, respectively, at the right and left sides as indicated in Fig. 7. Since both of these gauges are alike only one of them will be described in detail. Gauge GL comprises a scale 40 having a primary indicator or graduation 41 which is parallel to the length of the lay. The scale is secured to an ear 15 and faces upwardly and may be a thin flat strip or the like fastened in any approved manner to the top of the ear. If the scale is in the form of flexible paper, metal foil, or a decalcomania it will adhere directly to the ear, but if the scale is in the form of a sheet metal plate, not shown, it can be held to the ear in appropriate manner.

Secured to the adjacent tie member 31 is a secondary indicator shown here in the form of an indexing pointer 42 having an elongated body 43 in which are formed vertically spaced vertical slots 44, see Fig. 2. A holding screw 45 passes through upper slot 44 and is tapped into the tie member 31 to hold the indexing pointer in fixed position with respect to the reed. Extending laterally from the body 43 is a pointing or indicator finger 46 which overhangs the scale 40.

In order to afford some means for adjusting the back and forth position of the pointing finger with respect to the member 31 an adjusting screw 47 is tapped into the member and formed with a reduced right end 48, see Fig. 3, passing through the lower slot 44. The indexing pointer may be made of flat spring metal and is held by its resilience against screw 47. Turning of the adjusting screw means 47 effects adjustment of the pointer finger 46 backwardly and forwardly relatively to the reed.

In operation, the loom will be run long enough to establish correct location of the fell, after which the loom will be stopped and the lay moved to its front center position. The fell of the cloth will cause relative rearward movement of the lower part of the reed with respect to the lay and will also cause movement of the indicator finger 46 with respect to the scale 40. Screw 47 is then manipulated until the pointing finger is directly over or vertically registered with the indicator or graduation 41. This alignment can be effected by looking down from a position above the hand rail. The finger 46 should be as close as possible to the scale 40 without touching the latter in order that the error of registering the indicators may be reduced to a minimum. The two indicators will then be correctly set with respect to each other, and weaving can be resumed.

When the loom is to be started up after a

period of stoppage during which rearward movement of the fell of the cloth is likely to occur the weaver will first move the lay to front center position to determine the relation of the indicators. If there has been any rearward movement of the fell of the cloth during the period of stoppage the reed will be pushed rearwardly beyond its correct position and the indicators will not register, and the indicator on the lay occupying some such rearward position as indicated in Fig. 5. The weaver then manipulates the take-up mechanism, as by movement of the ratchet wheel 36, to move the cloth fell forwardly until the indicator 46 moves forwardly into register or alignment with the graduation or indicator 41, or to the position shown in Fig. 6. The relation of the reed with respect to the lay will then be the same as that which existed at the end of the previous period of loom operation, and the loom can be started up without producing a starting mark.

When the two parts, members, or indicators of the gauge are given their initial setting as already described hereinbefore they will ordinarily retain this setting so that it will not be necessary to alter the position of the reed carried indicator from day to day. If, for any reason, conditions in the loom should cause a slight change in the beat-up conditions a compensating adjustment of screw 47 will return the parts of the gauge into registry. Experience has shown that persons possessed of little or no skill in weaving are able by effecting register of the indicators as described to start up a loom without producing a starting mark in the cloth.

The continued use of the reed may eventually wear slight depressions in the forward edges of the reed dents, in which event it will be desirable to change the vertical position of the reed. It is for this reason that the bearings 18 are made to permit vertical adjustment. If the reed should be moved upwardly with respect to the lay to present a new part of the reed dents to the fell of the cloth, the pointing finger or indicator 46 can be lowered relatively to the reed by means of screw 45 so that it will be close to the graduation or indicator 41. Likewise, if the reed should be lowered the pointing finger will be adjusted upwardly relatively to the reed to avoid direct engagement with the scale 40.

Another important feature of the invention relates to the equalization of the forces of beat-up at the two ends of the reed. It will be understood that the spring 29 and the parts associated therewith shown in Fig. 3 are duplicated at the opposite end of the loom. Ordinarily the weaver cannot determine whether these springs both exert the same forward force on the opposite ends of the backstay 26. When each side of the loom is provided with one of the reed setting gauges as set forth hereinbefore, however, it is a simple matter to equalize the springs.

To effect this equalization the lay will be moved to a position slightly behind front center in which position the indicators 46 will be forward of the graduations or indicators 41 by approximately the same amount, since the reed under these conditions is not affected by the fell of the cloth and is aligned with the lay by springs 29. The lay is then moved to front center position and the position of the two indicators 46 compared with respect to their indicators 41. If, for instance, it should be found that the indicator 46 of gauge GR is farther behind its indicator 41 than the left indicator 46 is behind its indicator 41 the weaver will know that the spring 29 at the right

side of the loom is too weak. The weaver can then tighten the adjusting nuts 30 at the right side until both indicators 46 bear the same relation to or register with their respective indicators on the lay. This will indicate that both springs 29 are exerting the same forward force on the fell of the cloth, and the beat-up will be the same on both sides of the loom. It is to be understood of course that if it were thought desirable to weaken the strong spring a reverse adjustment would be made.

This adjustment of the springs of the swing reed, while described in detail with reference to the preferred form of the invention can be made with equal facility with either of the other forms to be described. The adjustment may be made preferably before the previously described setting of the reed carried indicators to prevent starting marks so as not to interfere with such setting.

Figs. 2 and 3 show one form of mounting for a swing reed but there are various other forms one of which is shown in Figs. 8 to 11. The modified forms of the invention are shown as applied to this second form of swing reed, but it is to be understood that the forms of the gauge set forth herein are not necessarily limited in their use to the two types of swing reed mountings described herein.

Referring particularly to Figs. 9 and 10, the lay 59 is provided with a lay end 51 on which is mounted a bearing 52. The latter is held to the lay end by upper and lower bolts 53 and 54, respectively, which pass through horizontal slots 55 in the bearing and through the lay end and are provided at their rear ends with nuts 56. The bearing member 52 has a bearing hub 57 which receives a gudgeon or trunnion 58 on a plate or reed hanger 59. This plate 59 is parallel to a second plate 60 formed as part of a hand rail mounting member 61. Upper and lower screws 62 and 63, respectively, secure the plates 59 and 60 together and pass through horizontal slots 64 in the plate 59 and are tapped into the plate 60, see Figs. 9 and 11.

The back and forth position of plate 60 with respect to plate 59 can be determined by an adjusting set screw 65. For any given relative setting of the two plates 59 and 60 they will be tightly secured to each other and move as a unit angularly with respect to the lay about the axis of gudgeon or stud 58.

Mounting member 61 has a side plate 67 slotted as at 68 to receive a bolt 69 the forward end of which is provided with a wing nut 70. Bolt 69 passes through the hand rail 71 which supports the upper end or edge of reed 72. The bottom of the reed, designated at 73, is held by the hanger 59 and can be acted upon by the same type of spring mechanism already described in connection with Figs. 1 to 7, or any other form of yielding or resilient means, which will tend to hold the bottom of the reed forwardly against the lay but permit rearward movement of the reed relatively to the lay by the cloth fell as has already been described.

The first modified form of the gauge comprises two angle members 75 and 76 which can be arranged as shown more particularly in Figs. 9 to 11. Gauge member 75 can conveniently be made of sheet metal and has an upright body 77 the lower end of which has a foot 78 perforated as at 79 to receive the screw 62. The perforation 79 may be somewhat larger than the screw, as indicated in Fig. 11, to permit ease of

adjustment of the part 75 both vertically and horizontally with respect to the plate 59.

The top of the gauge member 75 is bent generally horizontally and laterally to the left, see Fig. 9, to form a wing 80 which may if desired be inclined slightly downwardly and forwardly. Extending across the top of this wing and preferably parallel to the lay is a graduation, indicator or mark 81 which corresponds to the pointing finger or indicator 46 already described.

The other gauge member 76 is provided with a vertical body 82 having a downwardly opening slot 83 in a foot 84 at the lower end thereof through which the top bolt 53 passes. The upper part of the gauge member 76 has a wing 85 bent forwardly, see Fig. 9, and preferably inclined similarly to wing 80. Wing 85 is provided with a graduation, indicator or mark 86 which may be parallel to the lay and similar to indicator 81. Indicators 86 and 81 may be considered as primary and secondary indicators, and can conveniently be struck into their respective wings as linear grooves.

The gauge member 75 is adjustable angularly with respect to plate 59 in a back and forth direction, or in a direction parallel to the plane at which the reed swings. Gauge member 76, which is held under the head of bolt 53, can be adjusted in a right and left hand direction as viewed in Fig. 9 to move its wing 85 toward or from wing 80. Gauge member 76 is also vertically adjustable on the lay to enable both wings 80 and 85 to be at the same level by proper manipulation of the bolt 53. The two wings can therefore be placed in close proximity to each other without actual engagement.

The settings of the two gauge parts 75 and 76 of the first modified form of the invention will be similar to those already described for the preferred form of the invention. The graduations or indicators 81 and 86 will be caused to align when the lay is on front center after normal weaving conditions have been established. This alignment can be made by angular adjustment of the gauge part 75 and manipulation of screw 62, and after this adjustment is once made it will ordinarily not be necessary to change it.

After a period of loom stoppage the lay will be moved to its front center position and if there has been rearward movement of the fell of the cloth the graduation 81 will be slightly in advance of graduation 86. The take-up can then be manipulated until the fell of the cloth advances to a point where the two graduations or indicators 81 and 86 will be in lineal alignment, after which weaving can be resumed with assurance that no starting mark will be produced in the cloth.

As shown in Fig. 12 the type of gauge shown in Fig. 9 can be applied to each end of the lay or reed for the purposes already described in connection with the preferred form of the invention. In Fig. 12 it should also be noted that lineal alignment of the indicators or marker lines 81 and 86 will be visible throughout quite a wide visual angle. If the weaver is at the left end of the loom the alignment can be determined from any point in the angle such as that designated at *a*, and if at the right hand end of the loom the alignment can be seen throughout angle *b*. If the weaver is in front of the loom the alignment of the graduations or indicators 81 and 86 can be determined from almost any position in space *c* which the weaver will normally occupy. It will thus be seen that

the gauge shown in the first modification of the invention does not require a vertical line of vision as is the case in the preferred form of the invention.

5 The second modification may be used in connection with the same form of swing reed suspension set forth in Figs. 9 to 11, but instead of having upwardly extending gauge members as in the first modification the gauge members extend downwardly, and furthermore, the gauge members are identical.

10 Referring to Fig. 15, the two gauge members used in the second modification of the invention are designated at 90 and 91. These members are identical and may be made of sheet metal bent to form a vertical wall or foot 92 and a horizontal shelf or wing 93. Wall 92 has a slot 94 to fit either of the fastening means constituted by the bolt 54 or screw 63. The wing 93 has a primary indicator 95 parallel to wall 92 and a secondary indicator 96 at right angles to wall 92 and indicator 95. These indicators can be made in a stamping operation and be in the form of grooves.

15 When member 90 is held in place by bolt 54 with its wall parallel to the lay its primary indicator will be parallel to the lay, and when member 91 is held in place by screw 63 with its wall perpendicular or at right angles to the lay its secondary indicator will be parallel to the lay. The secondary and primary marks of members 90 and 91, respectively, will not be used. The slot 94 is such as to permit adjustments of each wing 93 relatively to the other and with respect to the support therefor.

20 It is believed that the operation of this second form of gauge will be understood without extended description. It operates in a manner very similar to the first modified form of the invention except that the aligned indicators are below the pivot of the swing reed. Since both members 90 and 91 are identical only a single type of indicator member need be made.

25 When the second modification of the invention is employed it can be located in a partly inclosed protected space or pocket 101 between plate 59 and a usual shuttle box mouth member or shuttle guard 102 which is secured as at 103 to a part of the bearing member 52. When thus located the indicator members 90 and 91 will not project beyond the space or pocket 101, and will be protected against accidental derangement.

30 From the foregoing it will be seen that the invention sets forth simple means by which the weaver may correctly locate the position of the swing reed with respect to the lay after a period of loom stoppage with assurance that when weaving is resumed there will be no starting mark in the cloth. Each form of the invention comprises essentially two indicators one of which may be considered a primary indicator on the lay and the other of which is a secondary indicator which becomes aligned with the primary indicator as the fell of the cloth due to manipulation of the take-up permits the swing reed to move forwardly relatively to the lay when the latter is on front center position. In the preferred form of the invention one of the indicators is over the other, but in the other two forms of the invention the indicators move into lineal alignment when registering. The invention is not necessarily limited to the forms of indicators shown herein and it will be sufficient if the lay and reed are each provided with a device which serves as a graduation, indicator, mark

or the like. In the second and third forms of the invention the lineal alignment can be seen from quite a wide visual angle and can be detected by the weaver from a position which is convenient for turning the take-up ratchet wheel. In all forms of the invention the fact that there is a gauge at each end of the reed permits an adjustment of the springs so that the amount by which they yield when the lay moves to front center can be equalized. In the second modification the indicator members are identical and can conveniently be located in a protected space or pocket which is found in the construction of certain types of lays provided with swing reeds.

Having thus described the invention it will be seen that changes and modifications of the foregoing specific disclosure may be made without departing from the spirit and scope of the invention.

What is claimed as new is:

1. In a loom having a take-up and a lay provided with a swing reed, gauge means for determining the position of the reed relatively to the lay comprising two indicator members capable of registry with each other, one of said members being on the lay and the other member moving with the reed and having the position thereof with respect to the member on the lay when the latter is on front center determined by the fell of the cloth, manual operation of the take-up when the lay is on front center effecting a change in the relative position of the members to effect registry of the latter.

2. In a loom having a take-up and a lay provided with a reed which is moved backwardly relatively thereto by the cloth fell when the lay is moved to front center position, means tending to move the reed forwardly relatively to the lay, a primary indicator on the lay, and a secondary indicator moving with the reed, manual operation of the take-up in a direction to advance the fell when the lay is on front center causing movement of the secondary indicator relatively to the primary indicator to the end that said indicators may be caused to register with each other.

3. In a loom having a take-up my manipulation of which the fell of the cloth can be moved backwardly or forwardly in the loom, a lay movable toward and from front center, a weft beat-up reed pivoted to the lay, resilient means holding the reed in normal position relatively to the lay when the latter is behind front center beat-up position but yielding to permit backward yielding of the reed relatively to the lay due to engagement of the reed with the fell of the cloth when the lay moves to front center beat-up position, a primary indicator on the lay, and a secondary indicator moving with the reed for registry with the primary indicator, manipulation of the take-up when the lay is on front center beat-up position causing movement of the reed relatively to the lay due to movement of the fell to effect registry of said indicators.

4. In a loom having a take-up and a lay element provided with a swing reed element, an indicator member on the lay element, a second indicator member on the reed element, the position of the second indicator member relatively to the indicator member on the lay element when the latter is on front center being determined by the fell of the cloth, and means affording back and forth adjustment of one of said members relatively to the corresponding element, manual operation of the take-up when the lay element is on front center effecting movement of the fell to

thereby determine the relative position of said indicator members.

5. In a loom having a take-up and a lay provided with a swing reed, means for adjusting the vertical position of the reed relatively to the lay, a primary indicator member on the lay, a secondary indicator member moving with the reed, and means to effect relative vertical adjustment of said indicator members to compensate for vertical adjustment of the reed relatively to the lay, manual operation of the take-up when the lay is on front center effecting relative back and forth movement of the indicator members to enable the latter to move into registry.

15 6. In a loom having a lay, a reed pivotally mounted on the lay, an adjustable spring means for each end of the reed, and gauge means for each end of the reed, each gauge means including an indicator on the lay and another indicator moving with the reed, movement of the lay to front center effecting rearward movement of the reed relatively to the lay by the fell of the cloth, and said gauges indicating the amount of rearward movement of each end of the reed

20 25 relatively to the lay, to the end that said spring means may be adjusted to cause the same degree of rearward movement of each end of the reed relatively to the lay when the latter moves to front center.

30 7. In a loom having a lay, a reed pivotally mounted on the lay, a resilient positioning means on the lay for each end of the reed, adjusting means for each resilient positioning means, a primary indicator on the lay adjacent to each end of the reed, and a secondary indicator moving with each end of the reed for the corresponding primary indicator, the fell of the cloth upon movement of the lay to front center effecting rearward movement of the reed against the action

35 40 45 of said resilient positioning means, and said secondary indicators each indicating the amount of rearward movement of the corresponding end of the reed with respect to the lay to the end that said adjusting means may be varied to cause each of said resilient positioning means to exert the same force on the reed.

8. In a loom having a lay, a reed pivotally mounted on the lay, an adjustable spring means for each end of the reed tending to move the latter forwardly relatively to the lay, and a gauge for each end of the reed including a part on the lay and a part moving with the reed, the reed being held in normal forward position by the spring means and said parts of each gauge sus-

55 taining a given relation with respect to each other when the lay is behind the front center position thereof, the lay upon movement to front center position causing rearward yielding of each end of the reed by the fell of the cloth relatively to the lay against the action of said spring means

60 65 and thereby changing the relation of the parts of each gauge, to the end that adjustments may be made in the spring means should the gauges indicate that the ends of the reed are moved rearwardly relatively to the lay unequal amounts by the fell of the cloth when the lay is moved to front center position.

9. In a loom having a take-up and a lay provided with a reed capable of movement relatively thereto by the cloth fell, a graduation on the lay, and a pointer moving with the reed and movable relatively to said graduation when the fell of the cloth due to manipulation of the take-up when the lay is on front center beat-up position effects movement of the reed.

11

10. In a loom having a take-up and a lay provided with a swing reed, means on the lay constituting a graduation, and an indexing pointer on the reed above the graduation, the position of said indexing pointer with respect to the graduation when the lay is on front center being determined by the fell of the cloth, manual operation of the take-up when the lay is on front center effecting a change in the position of the pointer to effect vertical registry of the latter with the graduation.

11. In a loom having a take-up and a lay provided with a swing reed, means on the lay constituting a lineal indicator, means moving with the reed constituting a second lineal indicator the position of which with respect to the indicator on the lay when the latter is on front center is determined by the fell of the cloth, manual operation of the take-up when the lay is on front center effecting a change in the position of said second lineal indicator to effect lineal alignment thereof with the lineal indicator on the lay.

12. The combination set forth in claim 11 wherein the means on the lay comprises a member having a wing provided with the lineal indicator, and wherein the means moving with the reed comprises a member having a wing carrying the second lineal indicator, said wings being so related that the indications thereon are in horizontal alignment when the indicators are in register.

13. A pair of reed setting gauge parts for a loom lay having a horizontal fastening means extending transversely thereof and a swing reed element provided with a horizontal fastening means therefor extending longitudinally of the lay, one of said gauge parts having a foot for attachment to the lay by the first named fastening means and having an indicator thereon, and the other gauge part having a foot for attachment to the swing reed element by the second named fastening means and having an indicator thereon for registry with the first named indicator.

14. A pair of reed setting gauge parts for a loom lay having a horizontal fastening means extending transversely thereof and a swing reed element provided with a horizontal fastening means therefor extending longitudinally of the lay, one of said gauge parts having a foot for attachment to the lay by the first named fastening means and having a wing at the upper end thereof carrying an indicator, and the other gauge part having a foot for attachment to the swing reed element by the second named fastening means and having a wing at the upper end thereof carrying an indicator for registry with the first named indicator.

15. In a loom having a take-up and a lay having a box mouth and a swing reed including a plate transverse of the lay and spaced from the box mouth, an indicator located between the box mouth and said plate and secured to the lay, a second indicator also located between the box mouth and said plate and moving with the swing reed, the position of the second indicator when the lay is on front center being determined by the fell of the cloth, manual operation of the take-up when the lay is on front center effecting a change in the position of the second indicator to effect registry thereof with the first named indicator.

16. In a loom having a take-up and a lay having a box mouth defining a partly inclosed space with a mounting for a swing reed, an indicator

5 on the lay located in said space, a second indicator moving with the swing reed also located in said space and having the position thereof relatively to the indicator on the lay determined by the fell of the cloth when the lay is on front center, manual operation of the take-up when the lay is on front center effecting a change in the relative position of said indicators to the end that said indicators may be moved into registry with each other.

17. A pair of identical reed setting gauge parts for a loom lay having a horizontal fastening means extending transversely of the lay and having a swing reed provided with a second horizontal fastening means extending longitudinally of the lay, each of said parts having a vertical wall formed to fit either of said fastening means and having a horizontal wing extending from the wall provided with two indicators thereon at right angles to each other, one indicator of each gauge part being parallel to the wall of the corresponding part.

18. A gauge forming member for a loom lay having a horizontal fastening means extending transversely of the lay and a swing reed provided with a second horizontal fastening means extending longitudinally of the lay, said member having a vertical wall formed to fit either fastening means and having also a horizontal wing provided with one indicator parallel to the wall and a second indicator perpendicular to the wall, one of said members when held in position on the lay by the first fastening means having said one indicator parallel to the lay and another of said members when held in position by the second fastening means having the second indicator thereof parallel to the lay for registry with said one indicator of the first member by movement of the reed relatively to the lay.

19. A gauge forming member for a loom lay provided with a swing reed, said member having a wall for attachment to either the lay or swing reed and having a wing provided with a primary indicator parallel to said wall and a secondary indicator perpendicular to the primary indicator, one of said members when having the wall thereof secured to the lay parallel thereto having the primary indicator thereof parallel to the lay, and another of said members when having the wall thereof secured to the swing reed with the wall thereof perpendicular to the lay having the secondary indicator thereof parallel to the lay.

20. A gauge forming member for a loom lay provided with a swing reed, said member having a wall for attachment to either the lay or swing reed and having a wing provided with a primary indicator parallel to said wall and a secondary indicator perpendicular to the primary indicator, said member when having the wall thereof secured to the lay parallel thereto having the primary indicator thereof parallel to the lay, and said member when having the wall thereof secured to the swing reed with the wall thereof perpendicular to the lay having the secondary indicator thereof parallel to the lay.
